(57) **CLAIM**

The ornamental design for an imaging device with cover plate, as shown and described.

DESCRIPTION

FIG. 1 is a front, bottom, right isometric view of an imaging device with cover plate;

FIG. 2 is a rear, bottom, left isometric view thereof;

FIG. 3 is a front elevation view thereof;

FIG. 4 is a rear elevation view thereof;

FIG. 5 is a bottom plan view thereof;

FIG. 6 is a top plan view thereof;

FIG. 7 is a right side elevation view thereof; and,

FIG. 8 is a left side elevation view thereof.

The broken lines in the drawings depict portions of the imaging device with cover plate that form no part of the claimed design.
